**CASING FOR REFRIGERATION SYSTEM
CONDENSING UNITS OR THE LIKE**

Walter W. Hoyle, Fayetteville, and Curtis L. Tobin,
Chittenango, N.Y., assignors to Carrier Corporation,
Syracuse, N.Y.

Filed Dec. 2, 1971, Ser. No. 204,403

Term of patent 3½ years

Int. Cl. D23—04

U.S. Cl. D23—139

FIG. 1

FIG. 2

FIG. 3

FIG. 4

FIGS. 1 and 4 are respectively front and rear perspective views of a casing for refrigeration system condensing units or the like showing our new design;

FIGS. 2 and 3 are respectively a top plan view and a side elevational view of the casing on a reduced scale.

We claim:

The ornamental design for a casing for refrigeration system condensing units or the like, substantially as shown and described.
